CARRIER FREQUENCY SHIFT SIGNALING

Salvatore A. Barone, Freeport, N. Y., assignor, by
mesne assignments, to Jefferson Standard
Broadcasting Company, a corporation of North
Carolina

Application April 23, 1946, Serial No. 664,168

7 Claims.

1

This invention relates to wave signalling systems and more especially to systems of signalling by carrier frequency shift.

A principal object of the invention is to provide an improved method and organization of apparatus for producing frequency-shift carriers whose mean frequency is maintained at an accurately predetermined value.

Another principal object is to provide a carrier frequency-shift radio transmitter wherein a highly stable carrier frequency source such as a crystal-controlled master oscillator, is subjected to a plurality of successive frequency modulation stages in such a way that the mean frequency of the shifted output carrier frequencies is maintained equal to the frequency of said source.

A feature of the invention relates to a carrier frequency-shift signalling system wherein keyed signals are simultaneously applied in successive stages of a frequency modulation system whose main exciting frequency is supplied by a suitable oscillator such as a crystal-controlled oscillator. The frequency relations of the said successive stages are such that at the output of the system there is produced shifted carrier frequencies having a highly stabilized mean frequency equal to that of said oscillator.

Another feature relates to a carrier frequency-shift transmitter having a main crystal-controlled carrier generator and a pair of local free-running oscillators, each of said running oscillators being simultaneously frequency-shifted under control of the same signal; together with means to modulate said main carrier by the frequency-shifted output of one local oscillator, and means to frequency-shift the modulated main carrier by the frequency-shifted output of the other local oscillator. By means of suitable frequency selector circuits such as band-pass filters or the like, there are selected at the output of the system frequency-shifted carriers whose mean frequency remains equal to the frequency of said crystal-controlled generator and is substantially independent of accidental changes in the said local oscillator circuits and associated equipment.

A further feature relates to an improved method of shifting carrier oscillations derived from a crystal-controlled oscillator so that the output carrier has a fixed mean frequency equal to the crystal frequency, the said output mean frequency being shifted equally in opposite directions with respect to the crystal frequency and

an amount of .21 cycle at the rate of 1000 cycles per second, the output of the oscillator being fed to a triode stage which is followed by a pentode stage which is fed into a final power amplifier. The stabilized oscillator is connected to the oscillator circuit of the transmitter and the power amplifier is connected to the antenna.

The oscillator circuit of the transmitter includes a crystal-controlled oscillator, a frequency multiplier, a frequency selector circuit, a modulator, and a power amplifier.

The frequency selector circuit includes a band-pass filter, a frequency multiplier, and a frequency selector circuit.

The modulator includes a modulator stage, a frequency multiplier, and a modulator stage.

The power amplifier includes a power amplifier stage, a frequency multiplier, and a power amplifier stage.

The power amplifier stage includes a power amplifier stage, a frequency multiplier, and a power amplifier stage.

The power amplifier stage includes a power amplifier stage, a frequency multiplier, and a power amplifier stage.

A still further feature relates to the novel organization, arrangement and relative interconnection of parts which cooperate to provide an improved and flexible carrier frequency shift telegraph system and the like.

Other features and advantages not specifically enumerated will be apparent after a consideration of the following detailed descriptions and the appended claims.

In the drawing which shows one preferred embodiment of the invention, there is represented by the numeral 10 any highly stabilized high frequency oscillator, such as a temperature-controlled crystal oscillator, which generates the desired master radio frequency "F". The output frequency of the system is indicated as $(F \pm 2\Delta f)$, where Δf is preferably in the audio frequency range, e. g., 400 C. P. S. This output can then be considered as two separate carriers, one having a frequency $(F - 2\Delta f)$ representing for example a telegraph space signal; and a frequency $(F + 2\Delta f)$ representing for example a telegraph mark signal. For the purpose of shifting the output frequency between the above-noted limits representing space and mark, there is provided any well-known keying device 11, which produces at the path 12 a D. C. voltage of for example a positive polarity and predetermined magnitude when keyed by a space signal and a D. C. voltage of negative polarity but the same magnitude when keyed by a mark signal. It will be understood of course, that the reverse may be true, that is, the space signal may be represented by the negative polarity and the mark signal may be represented by the positive polarity. In any event, and in accordance with the present invention, the output of the keyer 11 is divided into two paths 12, 13, and one path is designed to produce opposite polarity of voltages, with respect to that in the other path, as indicated schematically by the waves 14, 15.

The signal from path 12 is fed to any suitable reactance tube 16, so that the input voltages appear in the output of the tube as equivalent reactance variations. The magnitude of these reactance variations will, in the well-known way, be a function of the amplitude of the tone signal applied over path 12. For a detailed description of a typical reactance tube that may be used, reference is hereby made to application Serial No. 434,498, filed March 13, 1942, which issued April 9, 1946, as Patent No. 2,398,054. Likewise, the signal in path 13 which is in exact phase

6 opposition to the tone signal in path 12, is applied to a similar reactance tube 17.

Associated with the output of tube 16 is a local oscillator 18, which may be a "free running" oscillator that need not be controlled to the same degree of accuracy as oscillator 10, and which can have its output frequency varied in accordance with the reactance variations produced by tube 16. The local oscillator 18 may normally generate a frequency f , which by way of example may be thirty k. c. The oscillatory control circuit of oscillator 18 will include the plate reactance of tube 16 so that as the latter is varied by the signals from path 12, a corresponding change Δf is produced in the output frequency of oscillator 18. For a detailed description of one preferred manner of varying the frequency of oscillator 18, reference may be had to said application Serial No. 434,498. Consequently, there is produced an output frequency from oscillator 18 which is $(f \pm \Delta f)$ representing a telegraph mark signal, and $(f \mp \Delta f)$ representing a telegraph space signal. It will be understood of course, that when a mark signal is being keyed at device 11, the oscillator 18 may generate the frequency $(f \pm \Delta f)$, consequently when a space signal is being keyed at device 11, oscillator 18 generates the frequency $(f \mp \Delta f)$.

In a similar manner, the reactance tube 17 controls the frequency of a "free running" oscillator 19 which is similar to oscillator 18, and normally generates a frequency f . Likewise, the output of oscillator 19 is varied in frequency between $(f - \Delta f)$ and $(f + \Delta f)$. However, because of the phase opposition of the signals in paths 12 and 13, the frequency of oscillator 19 is changed in the opposite direction from the change in frequency of oscillator 18 for the same telegraph signal which is keyed at device 11. In other words, if for a space signal at device 11 the oscillator 18 produces a frequency $(f + \Delta f)$, then simultaneously the oscillator 19 produces a frequency $(f - \Delta f)$. Likewise, when oscillator 18 is producing a frequency $(f - \Delta f)$ corresponding to a mark signal at device 11, oscillator 19 is producing a frequency $(f + \Delta f)$.

The output of oscillator 18 is connected in balanced divided relation to any well-known balanced modulator 20, such for example as described in "Radio Engineering," by Terman, 1st edition, page 551, published by McGraw-Hill Book Company, Inc., New York, N. Y. Modulator 20 is also fed with the frequency F from the crystal oscillator 10. These two frequencies are mixed in the device 20 in the well-known manner so as to produce in the output the sum and difference frequencies. In this type of modulator, the frequency F is suppressed in the output. The double beat frequencies from the modulator 20 are applied to a band-pass filter 21, which passes for example only the higher beat frequency, namely $F + (f \pm \Delta f)$ as indicated in the drawing.

The shifted frequency from oscillator 19 is likewise fed in balanced divided relation to another balanced modulator 22, which is also fed with the $F + (f \pm \Delta f)$ signal from filter 21. Because of the balanced modulator action of device 22, the frequency $F + (f \pm \Delta f)$ is suppressed in the output. However, there are present at this output two beats, namely $[F + (f \pm \Delta f) + (f \pm \Delta f)]$ and

$$[F + (f \pm \Delta f) - (f \pm \Delta f)]$$

One of these beats, for example the lower beat is selected for passage by the band-pass filter 23. The net result is that the frequency at the output

terminals of filter 23 is $(F + 2\Delta f)$ representing a space signal at device 11; and $(F - 2\Delta f)$ representing a mark signal at device 11. It will be observed therefore, that the mean frequency F of these two output carrier frequencies always remain equal to, the said frequency F of the master oscillator 10; and this mean frequency remains stable notwithstanding undesired variations in temperature, humidity and similar conditions affecting oscillators 18 and 19 and their associated equipment.

By the expression "free running" as employed in the claims, is meant an oscillator which can be set to generate normally a particular frequency but which frequency can be varied by means of a signal; as distinguished from a fixed frequency oscillator such as a crystal controlled oscillator.

While one particular embodiment has been described, it will be understood that various changes and modifications may be made therein without departing from the spirit and scope of the invention.

What is claimed is:

1. The method of signalling which comprises, generating a master frequency F , generating a pair of local auxiliary frequencies each of frequency f , frequency-modulating both said local frequencies by the same signal but in opposite respects to produce respective side bands $(f \pm \Delta f)$ and $(f \mp \Delta f)$, mixing the $(f \pm \Delta f)$ frequency from one local oscillator with said master frequency F , and selecting one side band alone, mixing the said selected side band with the frequency $(f \mp \Delta f)$ from the other local oscillator, and selecting therefrom a side band component $(F \pm 2\Delta f)$.

2. The method of transmitting a telegraph signal by carrier frequency shift which comprises, generating a master frequency F which represents the mean between the limits of the shifted carrier frequencies to be transmitted, mixing with said master frequency a frequency f from a local "free running" carrier source whose frequency is shifted a predetermined amount and direction in accordance with a telegraph signal such as a mark signal, selecting one side band of the resulting mixture, mixing with said selected side band a carrier frequency f from another local "free running" carrier source whose frequency is simultaneously shifted said predetermined amount in accordance with said signal but in the opposite direction, and selecting from the resulting mixture a frequency in the range $(F \pm 2\Delta f)$.

3. The method of transmitting a telegraph signal such as a mark signal by carrier frequency shift which comprises, generating two "free running" carriers each of the same frequency f , simultaneously shifting the frequency of both carriers but in opposite frequency directions by said signal, generating a master frequency F , mixing with said frequency F the shifted frequency from one of said "free running" carriers and selecting one side band therefrom, mixing with said selected side band the shifted frequency from the other of the "free running" carrier, and selecting from the last-mentioned mixture the band represented by $(F \pm 2\Delta f)$.

4. In a carrier frequency shift signalling system, a source of master frequency F , a pair of local "free running" oscillators each normally generating the same frequency f , a source of telegraph signals, means responsive to a given telegraph signal such as a mark signal for simultaneously shifting the frequencies of said local oscillators substantially the same amount but in

opposite frequency directions, means to mix the output of one oscillator with said master frequency F and to select one side band from the resultant mixture, means to mix said selected side band with the shifted frequency from the other local oscillator, and means to select from the last-mentioned mixture a frequency in the range $(F \pm 2\Delta f)$, where Δf represents the extent of frequency shift in said local oscillators.

5. In a carrier frequency shift signalling system, a source of master carrier frequency F , a telegraph tone keyer, a pair of shiftable frequency local oscillators each normally generating the same frequency f , means to apply keyed tone signals simultaneously to both said oscillators to shift their respective output frequencies substantially equal amounts but in opposite directions, a first balanced modulator which is fed with said master frequency F and with the shifted frequency from one local oscillator, means to select from the output of said first balanced modulator a sideband frequency $F+(f \pm \Delta f)$, another balanced modulator which is fed with a selected side band from the first balanced modulator and with the shifted frequency from the second local oscillator, and means to select from the output of said second balanced modulator a band represented by $(F \pm 2\Delta f)$ where Δf represents the extent of frequency shift in said local oscillators.

6. In a carrier frequency shift signalling system, a source of master frequency F , a source of keyed telegraph signals, a pair of balanced modulators, a plurality of separate paths leading from said keyer respectively to said balanced modulators, each of said paths including in series a local shiftable frequency oscillator and a reactance tube, each oscillator generating normally the same frequency f , means to vary the plate reactances of the tubes in said paths to produce opposite frequency shifts in said local oscillators under control of said keyed signals, a selector system in the form of a band-pass filter for selecting from the output of the first balanced modu-

lator a sideband $F+(f \pm \Delta f)$ and a selector system in the form of a band-pass filter connected to the output of the second balanced modulator for selecting a frequency in the range $(F \pm 2\Delta f)$ where Δf represents the extent of frequency shift in said local oscillators under control of said keyed signals.

7. In a carrier frequency shift signalling system, a source of master frequency F , a local shiftable frequency oscillator of normal frequency f , a first mixing network upon which the said master frequency F and said local oscillations are impressed said mixing network acting to suppress said frequency F , means to shift the frequency of said local oscillator over the range $(f \pm \Delta f)$ under control of one telegraph signal, means to select from the output of said first network a frequency band $F+(f \pm \Delta f)$, a second local shiftable frequency oscillator of normal frequency f , a second mixing network upon which the said frequencies $F+(f \pm \Delta f)$ are impressed together with the oscillations from said second oscillator, said second network acting to suppress the range of frequencies $F+(f \pm \Delta f)$, and means to select from the output of said second network a frequency in the band $(F \pm 2\Delta f)$.
